United States Patent Office

Des. 211,933
Patented Aug. 13, 1968

211,933

DISPENSING CONTAINER FOR POWDER OR THE LIKE

Willard R. Horne, Northvale, N.J., assignor to Johnson
& Johnson, a corporation of New Jersey

Filed Dec. 12, 1966, Ser. No. 5,024

Term of patent 14 years

(Cl. D9—144)

FIG. 1.

FIG. 2.

FIG. 3.

FIG. 4.

FIG. 1 is a front elevational view of a dispensing container for powder or the like showing my new design;

FIG. 2 is a side elevational view thereof;

FIG. 3 is a top plan view thereof; and

FIG. 4 is a bottom plan view thereof.

I claim:

The ornamental design for a dispensing container for powder or the like, as shown.
